UNITED STATES PATENT OFFICE.

ELMER E. CONNER, OF ROANS PRAIRIE, TEXAS.

FENCE-POST.

1,122,367.

Specification of Letters Patent. Patented Dec. 29, 1914.

Application filed November 5, 1913. Serial No. 799,348.

To all whom it may concern:

Be it known that I, ELMER E. CONNER, a citizen of the United States, residing at Roans Prairie, in the county of Grimes and State of Texas, have invented certain new and useful Improvements in Fence-Posts, of which the following is a specification, reference being had to the accompanying drawings.

This invention comprehends certain new and useful improvements in fence posts and has for its primary object to provide a post which may be of extremely simple construction and operation and especially adapted for use in constructing wire fences.

Another object is to provide a fence post of this character which will be composed of a small number of parts of extremely simple and cheap construction and which will have one longitudinal edge provided with suitable serrations, whereby longitudinal movement of the wire clamping members upon the post will be prevented.

A further object is to generally improve and simplify the construction of devices of this character and increase the efficiency of the same without increasing the cost of manufacture of the device.

With the above and other objects in view, my invention consists in certain novel constructions, combinations, and arrangements of parts to be hereinafter more fully described, claimed, and illustrated in the accompanying drawings, in which,

Figure 1 is a front elevational view of my post in use; Fig. 2 is a side elevational view thereof; Fig. 3 is a fragmentary detail sectional view on the line 3—3 of Fig. 1; and Fig. 4 is a front elevational view of a modified form of the device.

Referring more specifically to the drawings in which similar reference characters designate corresponding parts throughout the several views, 1 designates the central portion and 2 the legs of the U-shaped metallic member forming the post, the central portion 1 of said U-shaped member forming the upper end of the post while the legs 2 of said member form the body of said post and are connected at spaced intervals by the bolts 3 or other suitable means. The lower ends of the legs 2 are curved outwardly, as shown at 4, to form anchoring means for the post, as will be clearly understood. Additional anchoring members 5 are provided which are herein shown as in the form of

plates, disposed upon opposite sides of the post at the lower ends thereof, the width of said plates being wider than the space between the side portions of the posts, so that the plates will bear upon the edges of the side portions 2 and when securely fastened by means of the bolts 6, will be held against any lateral movement. The lower ends of the anchoring members 5 are curved outwardly, the curvature corresponding to the curvature of the side portions 2, thus providing additional anchoring means for the post.

One longitudinal edge of each leg 2 is serrated, as shown at 7, to provide recesses to receive the fence wires 8. Each fence wire 8 is held in position against the serrated edge of the post by means of a link member 9 extending transversely between the legs 2 and having one end engaged around the wire 8 while the wedge key 10 is engaged transversely through the opposite end of said link, the wedge key 10 bearing against the smooth longitudinal edges of the legs 2.

It will be understood that each link member 9 is preferably open, in order that the same may be readily engaged over the wire 8 or removed from the same. It will further be evident that when the post is planted, the lower outwardly curved ends 4 of the legs 2 and the members 5 will serve as anchoring means for the post and thereby retain the same in upright position.

It will be apparent that if desired, the anchoring members 5 may be dispensed with, thereby providing the post formed of a single strip of metal and extremely light in weight, as well as strong and durable and cheap to manufacture.

In Fig. 4 I have illustrated a modified form of the invention, wherein the body of the post includes a plurality of spaced strips 11 which are suitably connected together by means of the bolts 11' and retained in spaced relation by means of the spacing blocks 12 arranged between each of the strips. In this form of the invention, the strips are not connected at their upper ends, as in the preferred form and it will be understood that any number of these strips may be used in constructing a single post. In providing anchoring means for a post of this character, the two outer strips are provided at their lower ends with the curved portions 12 which curve outwardly away from the

body of the post and are adapted to be disposed beneath the surface of the earth. It will be understood that the same means is provided in this form for securing the fence wires to the post as employed in the first or preferred form.

While I have shown the preferred embodiment of my invention, it will be understood that I do not wish to be limited 10 to the same as minor changes in the details of construction may be made within the scope of the appended claims without departing from the spirit of my invention or sacrificing any of the appended claims.

15 What I claim is:—

1. A fence post comprising a strip returned upon itself to form a U-shaped standard, the members of which are arranged in spaced relation to each other and 20 which have their lower ends curved laterally in divergent relation to each other to form anchoring members for the base portion of the standard, detachable plates adapted for engagement with the edges of 25 the standard members at the base thereof, said plates having their lower ends curved outwardly away from each other to form additional anchoring members terminating in a plane substantially the same as the 30 lower ends of the standards, the curved portions of said plates being disposed at right angles to the lower ends of the standard, whereby to prevent swaying or tilting movement of the standard, and tie bolts

extending through said plates from one to 35 the other and exerting an inward tension thereon, whereby to brace them against the opposite side edges of the standard and hold said plates securely in position.

2. A fence post comprising a strip returned upon itself to form a U-shaped standard, the members of which are arranged in spaced relation to each other and which have their lower ends turned laterally in divergent relation to each other to 45 form anchoring members for the base portion of the standard, plates engaging the edges of the standard members at the base thereof, said plates having their lower ends turned outwardly from each other to form 50 additional base members, and tie bolts extending through said plates from one to the other and exerting an inward tension thereon whereby to brace them against the opposite side edges of the standard members 55 and hold said plate securely in position, the standard members being serrated on one edge whereby the engagement of the serrated portions with one of said plates will additionally serve to hold said plates in 60 position and prevent any upward or downward displacement thereof.

In testimony whereof I hereunto affix my signature in the presence of two witnesses.

ELMER E. CONNER.
